UNITED STATES PATENT OFFICE.

CLARENCE GRIFFITH STOLL, OF OAK PARK, ILLINOIS, ASSIGNOR TO WESTERN ELECTRIC COMPANY, INCORPORATED, OF NEW YORK, N. Y., A CORPORATION OF NEW YORK.

FEEDING-DEVICE FOR STRAND MATERIAL.

Application filed October 25, 1923. Serial No. 670,804.

This invention relates to improvements in feeding devices for strand material, and more particularly to such a feeding device which may be used as a pulling element or capstan.

5 Heretofore it has been the usual practice to design capstans or other feeding elements of the drum type either with a sloped periphery, whereby each succeeding turn of strand material cramped the turns of material already on the drum down the inclined face thereof, or to provide a drum with a flat periphery and an element for pushing across the face thereof the turns of strand material wrapped thereon. Both of these 10 forms of feeding devices depend for their action upon a cramping of the turns of strand material, which in many instances damages it. To avoid this squeezing and consequent damaging of the strand material 15 grooved capstans have been provided, the grooves separating the strand material, but in order to secure a feeding of the strand material thereacross it was necessary to provide a pair of such drums around both of 20 which the strand material was looped back and forth. This construction is expensive and results in a bending and straightening of the strand material a multiple number of times, which in some instances is very 25 objectionable, such as the reeling of electrical conductors made of copper where a repeated bending and straightening thereof is detrimental to its tensile strength. In addition 30 the two drum arrangement occupies considerable floor space.

An object of this invention is to provide a feeding device comprising a drum or capstan adapted to receive a plurality of adjacent turns of strand material and so designed that all the friction and cramping 35 incident to the side slip of strand material during its passage across the drum, is avoided.

Another object of the invention is to provide a drum or capstan adapted to receive a plurality of adjacent turns of strand material with means for positively feeding the coils of strand material across the drum.

50 Other objects and advantages of the present invention will more fully appear from the following description and will be particularly pointed out in the appended claims.

In the accompanying drawings,

Fig. 1 is a vertical sectional view, partly in elevation, of a feeding device or capstan 55 made in accordance with the invention;

Fig. 2 is an elevation thereof partly in section;

Fig. 3 is an enlarged fragmentary vertical sectional view taken on the lines 3—3 60 of Fig. 2;

Fig. 4 is an enlarged fragmentary horizontal sectional view of one of the endless members, and

Fig. 5 is an enlarged fragmentary side 65 elevation thereof.

Referring now to the drawings in detail in which like reference numerals designate similar parts throughout the several views, 10 and 11 indicate oppositely faced cup-shaped members which comprise the ends of a feeding device or capstan made in accordance with the invention, these ends being held in spaced relationship by means of an annular ring 12 which has its edges grooved 70 as indicated at 13 (Fig. 3) to rest upon flanges formed on the cup-shaped members, the ring being securely positioned by means of screws 14 or other suitable means. The joint between the cup-shaped members 10 75 and 11 and the annular ring 12 is, as shown, of such character, that the outer surface of the cup-shaped members and the annular ring 12 are flush. The corners of the cup-shaped members 10 and 11 are rounded as 80 shown in Fig. 3, the purpose of which will 85 hereinafter appear.

The end members 10 and 11 and annular ring 12 constitute a drum and the said end members are provided with bosses 15 and 90 16 (Fig. 1) to provide bearings to receive a non-rotatable shaft 17 upon which the drum is free to rotate, being held in longitudinal position on the shaft by means of collars 18 and 19 pinned to the shaft.

95 Encircling the periphery of the drum are a plurality of belts 20 which are rotatably mounted upon idler pulleys 21. These pulleys are rotatably mounted upon stud shafts 22 secured in parallel ears 23 integral with the cup-shaped member 10 and adjacent the corner thereof. The endless belts 20 also pass around pulleys 24 which are fixed to stud shafts 25 rotatably mounted within suitable bearings formed in ears 26 integral 100 105 with the cup-shaped member 11 and adjacent

the corner thereof. Also fast upon the stud shafts 25 are spiral gears 27 which mesh with worms 28 mounted upon the outer ends of radially disposed shafts 29 which have on their inner ends bevel gears 30 which mesh with a bevel gear 31 pinned to the shaft 17. The belts 20 are disposed about the periphery of the annular member 12 disposed in shallow grooves made in said annular member, as shown in Figs. 1, 2 and 5, and the shafts 29 are arranged radially like the spokes in a wheel and have bearings formed in projections 33 and 34 made integral with the outer face of the cup-shaped member 11, as shown in Figs. 1 and 3.

The drum is driven by means of a worm wheel 35 secured to the boss 15 (Fig. 1) which meshes with a worm 36 connected with any suitable source of power (not shown).

In the operation of the pulling device or capstan a number of turns of strand material, which is shown in the drawings as comprising a cable 40, are wrapped about the drum and in contact with the belts 20. Each of the belts is provided with a plurality of projections 37 which are so positioned that the projections of all the belts are in spiral alignment around the periphery of the drum and when the turns of strand material are wrapped around the periphery of the drum, they lie in contact with the projections 37, as shown in Fig. 1. As the drum is rotated, through the medium of the worm 36 and worm wheel 35, the bevel gears 30 are rotated around the bevel gear 31 which is fixed to the non-rotatable shaft 17. The rotation of bevel gears 30 through the shafts 29 and worms 28 drive the bevel gears 27. These gears cause a rotation of pulleys 24 which serve to feed the belts 20 across the periphery of the drum, the projections 37 carried by the said belts engaging the turns of strand material on the drum and feeding them individually across the periphery of the drum. The projections 37 are so arranged that the turns of strand material are out of contact with each other whereby all cramping and friction on the strand material is obviated.

Where the improved pulley device or capstan is subjected to heavy loads, which might tend to cause the slipping of the belts 20, it may be found desirable to employ chains in place of the belts shown and sprockets in place of the idlers 21 and 24.

Although the capstan shown is particularly adapted for the reeling of electrical conductors or cables, it is not limited to this use and may be adapted for a variety of other purposes and the invention is only to be limited by the spirit and scope of the appended claims.

What is claimed is:

65 1. Strand feeding mechanism comprising

a rotatable member to receive a turn of strand material on the periphery thereof, and means movable relative to and in a direction substantially parallel with the axis of rotation of the said member for moving the strand material thereon across the periphery of the member.

2. Strand feeding mechanism comprising an annular member to receive a turn of strand material on the periphery thereof, and means movable across the periphery thereof for moving the received turn of strand material across the periphery of the annular member.

3. Strand feeding mechanism comprising a rotatable member to receive a turn of strand material on the periphery thereof, and means movable relative to the rotatable member for moving the strand material thereon across the periphery of the member, said means actuated by the rotation of said rotatable member.

4. Strand feeding mechanism comprising an annular member to receive a plurality of turns of strand material on the periphery thereof, and means carried by said annular member for individually feeding each turn of strand material across the periphery of said annular member.

5. Strand feeding mechanism, comprising a rotatable annular member to receive a plurality of turns of strand material on the periphery thereof, and means carried by said annular member for individually feeding each turn of strand material across the periphery of said annular member.

6. Strand feeding mechanism comprising a rotatable annular member to receive a plurality of turns of strand material on the periphery thereof, and means operated by the rotation of said annular member and carried thereby for individually feeding each turn of strand material across said annular member.

7. Strand feeding mechanism comprising an annular member to receive a plurality of turns of strand material on the periphery thereof, and means carried by said annular member and movable across the periphery thereof for feeding the strand material across the periphery of the annular member.

8. Strand feeding mechanism comprising a rotatable annular member to receive a plurality of turns of strand material on the periphery thereof, and means operated by the rotation of said annular member and carried thereby, said means movable across the periphery of said annular member for feeding the strand material thereacross.

9. Strand feeding mechanism comprising a rotatable annular member to receive a turn of strand material on the periphery thereof, and an endless member movable

across the periphery of the annular member for feeding the turn of strand material across the periphery of the annular member.

10. Strand feeding mechanism comprising a rotatable annular member to receive a plurality of turns of strand material on the periphery thereof, and an endless member movable across the periphery of the annular member for feeding the turns of strand material across the periphery of the annular member.

11. Strand feeding mechanism comprising a rotatable annular member to receive a plurality of turns of strand material on the periphery thereof, and an endless member driven by the rotation of said annular member, said endless member movable across the periphery of the annular member for feeding the turns of strand material thereacross.

12. Strand feeding mechanism comprising a rotatable annular member to receive a plurality of turns of strand material on the periphery thereof, and an endless member having projections thereon for engaging the turns of strand material on the periphery of the annular member, said endless member movable across the periphery of said annular member.

13. Strand feeding mechanism comprising a rotatable annular member to receive a plurality of turns of strand material on the periphery thereof, an endless member encircling the rim of said annular member in a transverse direction and in engagement with the turns of strand material thereon, and means for moving said endless member across the periphery of said annular member.

14. Strand feeding mechanism comprising a rotatable annular member to receive a plurality of turns of strand material on the periphery thereof, an endless member encircling the rim of said annular member in a transverse direction and in engagement with the turns of strand material thereon, and means operated by a rotation of the annular member for moving said endless mem-

ber across the periphery of said annular member.

15. Strand feeding mechanism comprising a rotatable annular member to receive a plurality of turns of strand material on the periphery thereof, a plurality of endless members encircling the rim of said annular member and in a transverse direction and in engagement with the turns of strand material thereon, and means for moving said endless members across the periphery of said annular member.

16. Strand feeding mechanism comprising a rotatable annular member to receive a plurality of turns of strand material on the periphery thereof, a plurality of endless members encircling the rim of said annular member and in a transverse direction and in engagement with the turns of strand material thereon, and means for moving said endless members across the periphery of said annular member at the same speed.

17. Strand feeding mechanism comprising a rotatable annular member to receive a plurality of turns of strand material on the periphery thereof, a plurality of endless members encircling the rim of said annular member and in a transverse direction and in engagement with the turns of strand material thereon, and means operated by the rotation of the annular member for moving said endless members across the periphery of said annular member.

18. Strand feeding mechanism, comprising a rotatable annular member to receive a plurality of turns of strand material on the periphery thereof, a plurality of endless members encircling the rim of said annular member and in a transverse direction and in engagement with the turns of strand material thereon, and means operated by the rotation of the annular member for moving said endless members across the periphery of said annular member at the same speed.

In witness whereof, I hereunto subscribe my name this 11th day of October A. D., 1923.

CLARENCE GRIFFITH STOLL.
